UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ELECTRICAL CONNECTING AND SUPPORTING DEVICE.

1,361,425.

Specification of Letters Patent.

Patented Dec. 7, 1920.

Application filed January 10, 1920. Serial No. 350,688.

To all whom it may concern:

Be it known that I, ERNEST CANTELO WHITE, a citizen of the United States, residing in the borough of the Bronx of the city of New York, in the State of New York, have invented certain new and useful Improvements in Electrical Connecting and Supporting Devices, of which the following is a specification, reference being had to the accompanying drawing, forming a part hereof.

This invention relates to electrical connecting and supporting devices useful under any conditions where it is sought to support an electrical device and connect it to a source of current. While the improved devices may be employed in connection with surfaces inclined at any angle to the horizontal and for the support of electrical attachments of any character, the invention is primarily concerned with the provision of an improved ceiling support for lighting fixtures.

The underlying thought of the invention is to provide a simple and sightly device which will permit lighting fixtures to be readily interchanged without skilful manipulation, the attachment of a fixture to the improved support serving at the same time to establish electrical connection between it and the current source. Such fixtures will be so constructed and standardized that they may be readily attached to standardized supports. In such cases it is proposed in accordance with the present invention to provide a sightly flush receptacle which will receive the improved electrical connecting and supporting devices and which, when not in use, will be entirely unobjectionable in appearance harmonizing with the supporting surface in such a pleasing manner as to be hardly noticeable. With a plurality of such receptacles in a single room fixtures may be readily supported removably at any desired place and the greatest enjoyment and the most effective lighting secured by reason of this portable character.

More particularly, the invention is concerned with a device which shall, mechanically and electrically, serve as a connector and support for attaching fixtures to ceilings and satisfy manufacturing requirements of simplicity and cheapness. Mechanically the support is based on a principle which may find embodiment in struc-

tures of great variety. Broadly, the structure includes a receptacle provided with a terminal, and a plug member including fixture supporting means and an inclined (illustrated herein as a curved) conducting and supporting member to enter the receptacle and engage the terminal, said receptacle and terminal including a bearing surface within the receptacle for the side of the conducting and supporting member nearest to the plug member, said receptacle and plug member also including coöperating means for resisting the turning moment of the conducting and supporting member about the said bearing surface by the force exerted on the fixture supporting means.

One embodiment of the invention is illustrated in the accompanying drawing, in which—

Figure 1 is a view in vertical section through a flush receptacle and showing the application thereto of the improved supporting and connecting devices, the view being taken along the plane indicated by the broken lines 1—1 of Fig. 5 and looking in the direction of the arrows.

Fig. 2 is a detail view in section through the improved supporting devices and taken on a plane at right angles to the plane of section of Fig. 1.

Fig. 3 is a view in horizontal section through the improved support taken on a plane indicated by the line 3—3 of Fig. 1 and looking in the direction of the arrows.

Fig. 4 is a detail view in elevation of one of the improved supporting conductors showing its relation to the insulating segment.

Fig. 5 is a view in horizontal section taken through the flush receptacle shown in Fig. 1 along the planes indicated by the broken lines 5—5 of Fig. 1 and looking in the direction of the arrows.

As stated hereinbefore, while the improved electrical connecting and supporting devices may find application to surfaces inclined at any angle to the horizontal and to electrical attachments of varied character, this application discloses the association of such devices with a lighting fixture which is to be suspended from a ceiling. As indicated in Fig. 1 the pendant support for a lighting fixture or other electrical attachment is indicated sufficiently by a fragment of a link *a* and an outlet box of approved

form is illustrated at *b*. The problem is to provide an electrical connecting and supporting device having universality of application to such pendant supports, as indicated at *a*, and to an outlet box or the like, such as is indicated at *b*. The front wall of the receptacle to be described, is illustrated as a face plate *c*, which is preferably made up of insulating material throughout, for a reason which will later appear, and may be fastened conveniently to the outlet box *b* by means of an interposed angle piece *d* secured to the outlet box *b* and to the plate *c* by means of screws *e*, *f*, respectively. Within the outlet box *b* and preferably secured to the reverse face of the plate *c* are two blocks *g*, *h*, of insulating material, secured together by means of bolts *i* and formed with recesses *g'*, *h'*, respectively, to receive suitable terminals *k*, *l*, respectively, which are in electrical connection with the main leads *k'*, *l'* of the source of current supply. The terminals *k*, *l* may conveniently be formed of opposed spring plates. The blocks *g*, *h* may be secured in place on the face plate *c* by means of suitable through-bolts *m*, the heads *m'* of which may rest in recesses formed in the face of the plate *c* in the interest of sightliness. The blocks *g*, *h* with the plate *c* constitute a receptacle.

The electrical connecting and supporting devices proper are formed, in accordance with the illustrated embodiment of the invention, as two reversely curved conductors *n*, *o* which may be passed through curved grooves *c'* formed in the face plate *c*. Each of these conductors *n*, *o* is secured at its lower end to a semicylindrical segmental block *o'*, *n'*, respectively, as by means of studs *o²*, *n²*, respectively, passing through the said blocks. As shown clearly in Fig. 3 the semicylindrical blocks *n'*, *o'*, are recessed on their meeting faces, as at *n³*, *o³*, respectively, to receive the conductors *n*, *o*, and their connecting studs *n²*, *o²*, and afford sufficient clearance between the parts so as to eliminate any chance of short circuiting at this point. The supporting studs *n²*, *o²*, may be used as terminal posts, being threaded at their inner ends to receive binding nuts *n⁴*, *o⁴*, respectively, by which the fixture leads *p*, *p'* are conveniently connected electrically to the conductors *n*, *o*. It is to be understood, however, that other means for attaching the conductors *n*, *o* to their respective blocks *n'*, *o'*, may be employed and such connecting means may be entirely independent of the electrical connections, if desired. Such details are matters of design and will be determined by electrical and mechanical considerations.

The two segmental blocks *n'*, *o'* are threaded exteriorly and when these blocks are placed together, with diametrical faces

in contact, they will constitute a true cylinder on to which may be threaded a locking ring *q* of any suitable form and connected mechanically with the pendant support *c*.

The details of one suitable embodiment for carrying out the invention having been described, the relation of parts for accomplishing the electrical connection and support between the electrical attachment and the flush receptacle will now be pointed out in such manner as to indicate the principle involved so that the scope of the invention may be better appreciated. The face plate *c*, it is to be understood, will be of slightly appearance and will lie substantially flush with the ceiling harmonizing therewith in such manner as to be practically unnoticed, so that when no fixture is associated with that particular outlet box *b*, the exposed surface of the plate *c* may be entirely unobjectionable. In this plate *c* will be observable the two slots *c'* which may be of comparatively small dimensions and which may be spaced from one another by a distance determined by the distance between the two conductors *n*, *o*. When it is desired to place the fixture in position, it will be selected to suit the fancy, it being understood that in the broadest aspect of the invention, it is proposed to have all fixtures equipped with some such universal connector as is exemplified by the ring *q*. The conductors *n*, *o*, will then be connected electrically to the fixture wires *p*, *p'*, the blocks *n'*, *o'* at this time being, of course, free from the ring *q*. One of the conductors, *n*, will then be passed up through its groove *c'* in the ceiling plate *c* and the other conductor *o* will then be passed up through its groove *c'* in the ceiling plate. In the illustrated embodiment of the invention, it is proposed to lay the conductors *n*, *o* out on arcs of circles struck about centers which, as viewed in Fig. 1, will lie on the periphery of the segments *n'*, *o'* or, perhaps, outside of these peripheries. Further, the grooves *c'* are laid out on arcs of circles struck about the same center and therefore concentric with the arcs of the circles on which the conductors *n*, *o* are laid out. In the illustrated embodiment, the conductor *n*, for instance, is struck off on the arc of a circle having its center at about the point *r*, so that in passing the conductor up through the curved groove *c'*, the block *n* will be so tilted and manipulated as to permit the curved conductor *n* to conform always to the curvature of the groove *c'*. As the conductors *n*, *o* are forced upwardly fully home they will be engaged by the opposed spring arms of the terminals *l*, *k*, respectively, thereby placing the fixture wires *p*, *p'*, in electrical connection with the source of current supply. With the conductors *n*, *o* fully home and the diametrical meeting faces of the segments *n'*, *o'* in contact, they will constitute a true cylinder on to which may be threaded a locking ring *q* of any suitable form and connected mechanically with the pendant support *c*.

n', o' in flush engagement, as illustrated in Fig. 3, the ring *q* may then be threaded on to the true cylinder formed by the segments, the upper edge of the ring finally bearing snugly against the face of the plate *c*. The side of the conductor *n* nearest to the plug *n'* will bear against the wall of the groove *c'*. The weight of the fixture will obviously set up a turning moment on the conductor *n* about its bearing surface on the wall of the groove *c'* which will tend to withdraw it about the center *r*. At the same time the weight of the fixture will set up a turning moment on the side of the conductor *o* nearest to the block *o'* about its bearing surface on the wall of the other groove *c'* which will act about the center of its curvature *r'*. These turning moments on the two reversely curved conductors *n, o*, which are lever arms, are equal and opposite and so will equalize one another. The weight of the fixture will then be transmitted directly to the face plate *c* and exerted thereon along the edges of the grooves *c'*. The stresses thus imposed on the plate *c* will be adequately resisted thereby and the fixture supported firmly in place. In this connection it may be desirable in all embodiments to provide the ring *q* at its upper edge with a flange, such as *q'*, which will bear against the face plate *c*, at points outside of the centers of curvature *r, r'* of the respective conductors *n, o*, this additional bearing surface setting up counter moments to the turning moments of the conductors *n, o* at such points as to lessen the stresses imposed on the plate *c*.

It has been sought herein to indicate the departures in form and relation which may be made in the elements while preserving their functions mechanically and electrically in the full sense contemplated by the principles on which the invention is based.

I claim as my invention:

1. An electrical connecting and supporting device including a receptacle formed with an entrance opening and provided with a terminal, and a plug member including fixture supporting means, a curved conducting and supporting member to engage the terminal and insulating means between the fixture supporting means and said conducting member, said receptacle and terminal including a bearing surface within the receptacle for the side of the conducting and supporting member nearest to the plug member, said receptacle and plug member also including coöperating means for resisting the turning moment of the conducting and supporting member about the said bearing surface by the weight of a fixture on the fixture supporting means.

2. An electrical connecting and supporting device including a receptacle formed

with entrance openings and provided with terminals, and a plug member including fixture supporting means, two conducting and supporting members inclined in different directions to engage the respective terminals and insulating means between the fixture supporting means and said conducting members, said receptacle and terminals including bearing surfaces within the receptacle for the sides of the conducting and supporting members nearest to the plug member, respectively, said plug member and fixture supporting means including coöperating means for resisting the turning moments of the conducting and supporting members about their respective bearing surfaces by the weight of a fixture on the fixture supporting means.

3. An electrical connecting and supporting device including a receptacle formed with entrance openings and provided with terminals, and a plug member including fixture supporting means, two curved conducting and supporting members extending in opposite directions to engage the respective terminals and insulating means between the fixture supporting means and said conducting members, said receptacle and terminals including bearing surfaces within the receptacle for the sides of the conducting and supporting members nearest to the plug member, respectively, said plug member and fixture supporting means including coöperating means for resisting the turning moment of the conducting and supporting members about their respective bearing surfaces by the weight of a fixture on the fixture supporting means.

4. An electrical connecting and supporting device including a receptacle formed with entrance openings and provided with terminals, and a plug member including fixture supporting means, two curved conducting and supporting members extending in opposite directions to engage the respective terminals and insulating means between the fixture supporting means and said conducting members, said receptacle and terminals including two curved grooves extending in opposite directions for the sides of the conducting and supporting members nearest to the plug member, respectively, said plug member and fixture supporting means including coöperating means for resisting the turning moments of the conducting and supporting members about their respective grooves by the weight of a fixture on the fixture supporting means.

5. An electrical connecting and supporting device including a receptacle formed with entrance openings and provided with terminals and a plug member including fixture supporting means, two conducting and supporting members, inclined in different

- directions, to engage the respective terminals, and insulating means between the fixture supporting means and said conducting members.
6. An electrical connecting and supporting device including a receptacle formed with two entrance openings and provided with terminals, and a plug member including fixture supporting means, two curved conducting and supporting members, extending in opposite directions, to engage the respective terminals, and insulating means between the fixture supporting means and said conducting members.
10. An electrical connecting and supporting device including a receptacle formed with an entrance opening and provided with a terminal, and a plug member including a fixture supporting threaded member, a curved conducting and supporting member to engage the terminal, and insulating means between said threaded member and said conducting member, the threaded member being supported by said insulating means, the plug member and fixture supporting member also including coöperating means for resisting the turning moment of the conducting and supporting member about the said bearing surface by the weight of a fixture on the fixture supporting member.
15. An electrical connecting and supporting device including a receptacle formed with entrance openings and provided with terminals, and a plug member including fixture supporting means, two conducting and supporting members, inclined in different directions, to engage the respective terminals, and two insulating blocks to which the conducting members are secured, respectively, and on which the fixture supporting means are carried, said plug member and fixture supporting means including coöperating means for holding the insulating blocks against movement relative to one another.
20. A receptacle for an electrical connecting and supporting device formed with entrance openings for curved conducting and supporting members of a fixture supporting plug member of the device, and provided with terminals to be engaged by said conducting and supporting members, said receptacle and terminals including bearing surfaces within the receptacle for the sides of the conducting and supporting members nearest to the plug member, respectively, said bearing surfaces being in such relation to the conducting and supporting members that the latter have turning moments about their bearing surfaces, respectively, by the weight of a fixture on the fixture supporting plug member.
25. A receptacle for an electrical connect-
- ing and supporting device formed with entrance openings for two conducting and supporting members of a fixture supporting plug member of the device, extending in different directions, and provided with terminals and bearing surfaces to be engaged by the conducting and supporting members.
30. A receptacle for an electrical connecting and supporting device formed with entrance openings for two curved conducting and supporting members of a fixture supporting plug member of the device, extending in opposite directions, and provided with terminals to be engaged by the conducting and supporting members, said receptacle and terminals including two curved grooves extending in opposite directions for the sides of the conducting and supporting members nearest to the plug member, respectively.
35. A plug for an electrical connecting and supporting device including fixture supporting means, a curved conducting and supporting member to enter a receptacle of the device and engage a terminal and bearing surface therein, insulating means between the fixture supporting means and said conducting member, and means to coöperate with the receptacle to resist the turning moment of the curved conducting and supporting member about its bearing surface by the weight of a fixture on the fixture supporting means.
40. A plug for an electrical connecting and supporting device including fixture supporting means, two conducting and supporting members inclined in different directions to engage terminals and bearing surfaces within a receptacle of the device, and insulating means between the fixture supporting means and said conducting members.
45. A plug for an electrical connecting and supporting device including fixture supporting means, two curved conducting and supporting members extending in opposite directions to engage terminals and bearing surfaces within a receptacle of the device, and insulating means between the fixture supporting means and said conducting members, said plug also including means to resist the turning moments of the conducting and supporting members about their respective bearing surfaces by the weight of a fixture on the fixture supporting means.
50. A plug for an electrical connecting and supporting device including fixture supporting means, two curved conducting and supporting members extending in opposite directions to engage terminals and bearing surfaces within a receptacle of the device, and two insulating blocks to which the respective conducting members are secured and on which the fixture supporting means

are carried, said plug and fixture supporting means also including means to hold the blocks against relative movement.

16. A plug for an electrical connecting and supporting device including a threaded fixture supporting member, two curved conducting and supporting members extending in opposite directions and adapted to en-

gage terminals and bearing surfaces within a receptacle of the device, and two insulating blocks to which the conducting members are secured, respectively, and on which the threaded member is screwed. ¹⁰

This specification signed this 19th day of December, A. D. 1919.

ERNEST CANTELO WHITE.
